UNITED STATES PATENT OFFICE.

FRANK W. WARD, OF LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR USE IN LASTING BOOTS AND SHOES.

1,400,703.

Specification of Letters Patent. Patented Dec. 20, 1921.

Application filed February 19, 1919. Serial No. 277,940.

To all whom it may concern:

Be it known that I, FRANK W. WARD, a citizen of the United States, residing at Lynn, in the county of Essex and State of Massachusetts, have invented certain Improvements in Machines for Use in Lasting Boots and Shoes, of which the following description, in connection with the accompanying drawings, is a specification, like reference characters on the drawings indicating like parts in the several figures.

This invention relates to machines for use in the lasting of boots and shoes and particularly to machines for use in the lasting 15 of stitch-down shoes.

As now constructed, machines for use in the manufacture of stitch-down shoes are provided with a combined work support and anvil block designed to support the work at 20 such an angle to the vertically arranged lasting tool that the upper can be wiped over the last and the marginal portion of the upper can be tucked well into the angle between the last and the sole during the lasting operations. This block is so mounted that its 25 angular relationship with respect to the lasting tool can be varied by adjustment, after which the block is secured in its adjusted position. The position thus selected for the 30 block is ordinarily satisfactory for lasting operations on various kinds of shoes. However, in going around certain parts of the last and particularly the heel portion, it is desirable to set the fastenings, which pass 35 through the lasting tool, at a greater angle than that provided by the block in its fixed position. The operative, in attempting to drive the fastenings as close as possible into the angle of the last and sole at the heel end 40 of the shoe, holds the shoe at a greater angle with respect to the lasting tool or nozzle than that defined by the work supporting anvil block in connection with said nozzle, with the result that in lasting operations the marginal 45 portion of the sole is bent downwardly all around the heel portion thereof since it is unsupported by the block, being tipped upwardly away from the block. A shoe lasted in the way described will have the heel portion of 50 the sole dished or cupped to a variable extent depending upon the angle at which the shoe was held and the kind of material used for soles. In certain grades of shoes where-

in the insole is of poor material, and in all heelless shoes, such as children's shoes, it is 55 necessary to place a piece of leather or leatherboard in the center of the cupped heel portion of the sole before applying the outer-sole. This is because the subsequent opera- 60 tions of laying and leveling the outersole would otherwise fail to remove permanently the cupped condition of the heel end of the sole, though immediately after the leveling operation the heel portion of the sole may appear perfectly flat. With the additional 65 piece inserted in the cupped end of the sole, the shoe can readily be finished so as to present the appearance desired, but the additional operation is objectionable since it adds to the cost of the shoe. In shoes which are 70 completed by adding a heel, the cupping of the heel portion of the insole during the lasting operation presents no distortion of the heel seat which is not corrected satisfactorily by the attachment of the heel. 75

It is an object of the invention to provide improved means for operating with the lasting tool so that the shoe will be progressively lasted without any cupping of the sole.

While the conditions attendant upon the 80 manufacture of certain grades or types of shoes occasioned the development of the invention, it will be understood that the invention is not thus limited in its applica- 85 tion and that it comprises in one broad aspect the provision of means arranged to co-operate with a lasting tool in lasting operations in such a way that the shoe will be fully and properly supported throughout the 90 wiping and fastening inserting operations, 95 whatever the angle at which the fastenings are driven.

In the illustrative embodiment of the invention, the means which co-operates with the lasting tool to effect lasting operations is disclosed as comprising a freely tilttable table or 95 work support designed to support the marginal portion of the sole during progressive lasting operations which include the driving of fastenings at various angles along the 100 toe, shank and heel portions of the sole.

One of the difficulties encountered in connection with a work support made freely adjustable to the various angles at which it is desired to drive fastenings is that of securing 105 the proper clenching of the fastenings

since under these conditions, the support has a distinct tendency to lateral displacement away from the line of drive of the fastenings at the time the fastenings are being clenched.

5 An important feature of the invention comprises the provision of means for insuring the proper setting of fastenings driven at various angles into work supported on a freely adjustable work support.

10 Other features of construction reside in an organization in which the work support is vertically movable to coöperate with a relatively stationary lasting tool and is thereafter stationary while clenching means 15 moves to clench fastenings driven through said tool, and in which a freely tiltable work support is associated with a clamping surface relatively movable with respect to said support to coöperate with the stationary tool 20 to clamp the work while fastenings are driven through work on the support.

From one viewpoint the invention resides in an improved work support which is reciprocable toward and from work clamping position and is freely movable about an axis and provided with a work supporting surface having an opening through which a tool operates on the work upon relative movement between the tool and the work 30 support.

Other objects and features of the invention will be apparent from the following detailed description and will be pointed out in the claims.

35 In the drawings,

Figure 1 is a front view of the upper portion of a lasting machine showing one embodiment of my invention;

Fig. 2 is an enlarged detail view of the 40 work supporting and clenching mechanism;

Fig. 3 is a view in perspective of a portion of the work support;

Fig. 4 is a perspective view of the block which presents a clenching surface and also 45 a work engaging surface;

Fig. 5 is a perspective view of the work supporting table; and

Fig. 6 is a view in side elevation of the entire machine.

50 In the illustrative machine the fastening inserting mechanism is shown as comprising wire feeding mechanism 10, fastening forming and driving mechanism including the nozzle 12, and means 14 for varying the size 55 of the fastenings which are made and driven by the fastening inserting mechanism. For a complete disclosure of the inserting mechanism reference should be had to Letters Patent No. 1,016,930, granted Feb. 13, 1912,

60 on an application of William H. Borden. In the machine organization, of which a fastening inserting mechanism forms an essential part, the nozzle 12 is constructed and arranged to operate as a lasting tool which 65 may be substantially as fully described in

the Letters Patent to Prenzel No. 1,117,087, dated Nov. 10, 1914. In lasting a shoe by the novel mechanism herein disclosed the upper is wiped down over the sides of a last progressively by the lasting tool 12 as the work 70 is presented thereto while supported by means arranged to coöperate with the lasting tool in lasting operations in such a way that the shoe will be fully and properly supported throughout the wiping and fastening 75 inserting operations whatever the angle at which the fastenings are driven. In the illustrative embodiment of the invention, the said means comprises preferably a tiltable work supporting block 16 pivoted at 18 80 upon a carrier 20 which comprises a tubular sleeve portion 22 arranged to fit slidably over the upper end of a post 24. The carrier comprises also a base plate 26 between which and the foot plate 28 of the post 24 there is 85 positioned a spring 30 of such a tension as to maintain the carrier in raised position against the pressure which is developed initially in wiping the upper over the last in the lasting operations. In order to retain 90 the carrier on its post and to limit the movements thereof, there is provided a pin 32 extending from the post 24 into a slot 34 in the carrier. As shown, the tiltable member 16 is pivoted to side pieces 36 of the carrier 95 and between said side pieces by short pivots which extend through the said side pieces and into and through the side bars 38 of the table 16, said side bars being formed incidental to the cutting away of the middle 100 portion of the table, as shown at 40, to provide for the accommodation of a member 42 which normally projects into the said opening. The member 42 is preferably carried by the upper end of the post 24, a convenient 105 arrangement in providing for the attachment of said member consisting in undercutting projecting portions 44 at the upper end of the post 24 in such a way as to receive the dovetailed projection 46 on the block and 110 hold the same firmly in sliding engagement in the passageway formed by the projecting portions or flanges 44. Since the pressure on the block 42 is always in a downward direction no other attaching means than that 115 provided by the dovetailed connection described is necessary. This construction has the further advantage that the block may be readily withdrawn and turned end for end, thus providing a new surface when the 120 one which has been in use becomes worn or for any reason unsuitable for further use. Preferably, therefore, the ends of the block have identical construction and each comprises clenching surfaces 48 and a work engaging rib 50 the functions of which will be 125 hereinafter described. In the construction shown the post 24 with its foot plate 28 is mounted for sliding adjustment as indicated at 52 in Fig. 1, means in the form of a bolt 130

54 being provided for securing the post in adjusted position on the work supporting post 84 hereinafter described.

Mounted in the head 60 is a driving shaft 562 having thereon the fast and loose clutch members 64 and 66 which are normally held in separated relation but are adapted to be placed in operative engagement by the wedge 68 connected by the rod 70 to the starting 10 and stopping treadle 72 pivoted to the base portion of the column 74 upon a pin or rod 76.

Secured to the column 74 by suitable means, such as the bolts 78, is a bracket 80 provided with bearing portions 82 in which is vertically movable the work supporting post 84. The lower portion of the work supporting post 84 extends below the lower bearing 82 and contacts with treadle controlled means whereby the work supporting post may be manually raised. In the present instance this means comprises a lever 86 pivoted at 88 to a lug 90 extending from the bracket 80, the rear end portion of said 25 lever being pivotally connected at 92 to a treadle 94, the fulcrum of which is preferably established on the pin or rod 76. The free end portion of the lever 86 is provided with an adjustable device upon which 30 the lower end of the work supporting post 84 rests. In the present instance this device comprises an adjusting screw 96 threaded into the lever 86 and provided with a hand piece 98 by which it may be turned to project 35 or retract its end portion 100 to regulate the drop of the work supporting post. When adjusted the screw 96 may be secured from accidental displacement by a clamping bolt 102 passed through the split end of the lever 40 86. In the illustrated machine the post 84 is provided with bearing portions which comprise lugs 104 secured to the post above the upper end of the bearing 82 in which the post slides, said bearing 104 being arranged 45 to engage the flat face 106 of an arm 108 adjustably secured to the bracket 80 by suitable means such as the bolts 110 which pass through elongated slots in the arm 108, the construction being such that 50 the arm 108 may be properly adjusted into bearing relation with the lugs 104 which may ride on the flat face of the arm as the post is raised and lowered. By this construction rotative movement of the work 55 supporting post is prevented and since the bearing between the lugs 104 and the arm 106 is close to the work supporting portion of the post, spring action of the post under the strain of inserting fastenings into the 60 boot or shoe is prevented.

In the use of the construction thus far described it will be apparent that upon depression of the treadle 94 the work supporting post 84, which as a whole may be conveniently termed the work support, will be

raised manually toward the fastening inserting mechanism to clamp the work against the opposed abutment which, in the illustrated stitchdown staple lasting machine, comprises the lasting tool 12. When the operative has satisfied himself that the desired wiping action of the upper about the last will be secured, and that the fastenings will be properly driven into the work, the starting treadle 72 will be depressed to set the fastening inserting mechanism into operation. In the illustrated machine means is provided which, upon starting into operation the fastening inserting mechanism, will insure that the work support is fully raised and locked in work clamping position provided that work support movement toward such position has been manually started or initiated. This means in the construction shown comprises a wedge yieldingly actuated from the means for operating the fastening inserting mechanism. Preferably the bracket 80 is provided with guideways 112, one at each side of the bracket 80 in each of which is mounted for reciprocating movement a wedge 114. Each guideway 112 may be formed by separated upper and lower flanges 116 which thus provide a passage between them for a pin 118 secured to each wedge 114. Connected to each pin 118 is a rocker arm 120 secured to a rock shaft 122 mounted in suitable bearings which may be conveniently formed in the bracket 80, sufficient play or loose motion being provided between the pins 118 and the connections to 90 permit rectilinear movement of the wedge without binding of the parts. The rock shaft 122 has secured thereto an arm 124 which may be yieldingly connected to suitable means actuated from the driving shaft 95 62 to impart to said arm 124, and through it and associated elements as described, to the wedges 114, the desired movements, as will presently appear. Secured to the main driving shaft 62 is a cam 126 having a cam path 100 engaged by a pin or roller mounted on an arm 128 which is mounted for rocking movement on the machine head. As shown the arm 128 is mounted on the pin or stud carried by bearings 130 projected from the head 115 frame 60, the construction being such that as the driving shaft is rotated and the fastening inserting mechanism is consequently operated, the arm 128 will be rocked by the cam 126. The arm 128 is yieldingly connected to the arm 124 above described, and in the present instance such connection is made by providing the arm 128 with lugs 120 for the support of a pin which passes through the upper end portion of the wedge 125 operating rod 132. The lower portion of the rod 132 passes loosely through the rocking stud mounted for rocking movement in the bearing carried by the arm 124 and has mounted on its end the set nuts 134. Sur- 130

rounding the rod 132 and seated at one end on the top of the said rocking stud and at its other end against the under side of a collar 136 adjustably secured to the rod 132, 5 is a spring 138, the construction being such that as the cam 126 is rotated by the main driving shaft 62, the rod 132 will be reciprocated to impart to the wedges 114 reciprocating movement in their respective guides 10 provided such movement of the wedges is not effectively obstructed. Should the wedges meet an effective obstruction sufficient to prevent such movement the rod 132 will still be reciprocated but, instead of 15 moving the arm 124 on the downward movement of the rod, the spring 138 will yield and simply be compressed, thus permitting the wedges to remain at rest. Projecting from the work supporting post 84 at the 20 sides thereof in front of the wedges 114 are pins 140 carrying rolls 142 for engaging the wedges 114 as the latter are moved forward by the automatic means described. When the work support is in its lowered position, 25 as when the treadle 94 is not depressed by the operative, the axes of the pins and rollers are slightly below the front edges of the wedge inclines, and if at such times the starting and stopping treadle 72 be depressed to start the machine, the moving means for the wedges will be operated but the rollers and pins in the work support will prevent such movement of the wedges and the work support will remain in lowered 30 position. Upon manually lifting the work support to or toward work clamping position, as by depression or partial depression of the treadle 94, then the axes of the pins and rollers will have been sufficiently raised 35 to permit the wedges to engage beneath them as the wedges are operated from the main shaft and thus the work support will be lifted to full work clamping position and locked for the insertion of fastenings. For 40 a more complete description of the automatic mechanism for operating the work supporting post, reference should be had to the co-pending application of Matthias Brock, Serial No. 44,915, filed August 11, 45 1915.

In performing lasting operations with the machine which has been described in detail, the operative will present the lasted shoe parts to the machine by placing the 50 work upon the tiltable work supporting block or table 16 which, because of the fact that it is freely pivoted, conforms itself instantly to the angle at which the work is presented. Hence the margin of the sole is fully supported at whatever angle it is desired to 55 drive the fastenings. The operative then depresses the treadle 94 to cause the work to engage with the lasting tool 12 which operates to wipe the upper down over the side 60 of the last and to tuck it into the angle be-

tween the last and the projecting margin of the sole. During the wiping and pressing operations which accompany the lasting of the upper, the carrier 20 for the tiltable table 16 yields slightly relatively to the post 70 24 so that at the termination of the wiping operation the upper is firmly clamped into the angle of the last and sole and upper and sole are finally pressed against the block 42 which carries the staple clinching cav- 75 ities. Thus, by relative movement between the tiltable table and the clinching block the latter operates to securely set the fastening in place, thus terminating the lasting operation. As heretofore described, the block 42 80 is provided with a projecting rib 50 which is constructed and arranged to engage the lower surface of the sole only after a slight relative depression of the tiltable table with its carrier so that by engagement of said rib 85 with the sole any lateral slipping movement of the work on the tiltable table is prevented. While the engaging rib thus described is not an absolutely essential feature of the construction, it has distinct advantages inasmuch as without such a rib the operative 90 must exercise considerable pressure laterally on the work to prevent it from slipping during the fastening inserting operation. By reason of the construction and arrangement 95 of the work support operating mechanisms the operative is enabled to start the lasting operation under manual control by depression of the treadle 94 but such manual control is quickly supplemented by the power 100 driven means for lifting the work support to effect the completion of the lasting operation, and especially the firm setting of the fastening under conditions which insure a 105 perfect clinching of the fastening while the work is securely clamped in lasted position.

Having thus described my invention, what I claim as new and desire to secure by Letters Patent of the United States is:

1. In a machine of the class described, 110 fastening inserting means, a freely tiltable work support movable toward and from the inserting means to present work thereto, and means movable relatively to said support for clinching fastenings driven through work 115 on said support.
2. In a machine of the class described, fastening inserting mechanism, in combination with a work support relatively movable with respect to the inserting mechanism to 120 permit of the insertion and removal of work and freely adjustable by manipulation of the work, and means independent of the work support for clinching the fastenings.
3. In a machine of the class described, 125 fastening inserting mechanism, a work support, means under the control of the operator for moving the work support toward and from the inserting mechanism to present the work thereto for the insertion of 130

- fastenings, and means movable relatively to the work support for clenching the fastenings.
4. In a machine of the class described, 5 fastening inserting mechanism comprising a stationary nozzle, a work support movable to press the work against said nozzle, and means independent of the work support and movable relatively thereto to clench the 10 fastenings.
5. In a machine of the class described, fastening inserting mechanism comprising a fastening driver and a nozzle, a work support movable to press the work against the 15 nozzle, means for moving the driver through the nozzle, and means movable through the work support to clench the fastenings.
6. In a machine for progressively lasting 20 a shoe, a lasting tool comprising a fastening guiding nozzle, and means comprising a freely movable member for coöperating with said lasting tool progressively to last the shoe, said member having a work positioning surface freely adjustable angularly to hold 25 the work at the desired angle with respect to the nozzle.
7. In a machine for progressively lasting a shoe, a lasting tool comprising a fastening guiding nozzle, a freely adjustable member 30 for coöperation with the lasting tool in lasting operations, and means independent of said member for clenching the fastenings.
8. In a machine for progressively lasting a shoe, a lasting tool comprising a fastening 35 guiding nozzle, a work support controlled by the presentation of the work thereto to support the work at any desired angle with respect to the lasting tool, and means movable relatively to the support for clenching the 40 fastenings.
9. In a machine for progressively lasting a shoe, a lasting tool comprising a fastening guiding nozzle, a work support freely tilttable to support the work at various angles during 45 the progressive lasting operations, means for causing relative movement of the work support and lasting tool, and means independent of the support for clenching the fastenings.
10. In a machine for progressively lasting 50 a shoe, a lasting tool comprising a fastening guiding nozzle, a freely adjustable work support to support the work at various angles during the progressive lasting of the upper, and means independent of the work support 55 for clenching the fastenings and for holding the work against lateral movement during the fastening clenching operation.
11. In a machine for progressively lasting 60 a shoe, a lasting tool comprising a fastening guiding nozzle, a work support freely adjustable to support the work in varying angular relationship to the lasting tool during the lasting operations, means for clenching the fastenings, and means independent of the
- work support for holding the work against 65 lateral movement during the fastening inserting operations.
12. In a machine for progressively lasting a shoe, a lasting tool comprising a fastening guiding nozzle, a freely tilttable work support for coöperation with the lasting tool to present the work thereto, and means movable through said work support for clenching the fastenings. 70
13. In a machine for progressively lasting 75 a shoe, a lasting tool comprising a fastening guiding nozzle, a work support freely adjustable angularly with respect to the lasting tool to present the work thereto at various angles during the lasting operations, means 80 for yieldingly pressing the work support against the lasting tool, and clenching means for clenching the fastenings.
14. A machine for progressively lasting 85 the upper of a shoe comprising a lasting tool having a fastening guiding passageway therein, a work support freely pivoted to present work to the lasting tool so that fastenings may be driven at various angles into the work, manually operable means for 90 pressing the work support against the lasting tool, means independent of the work support for clenching fastenings during the lasting operations, and power means for operating said clenching means. 95
15. In a fastening inserting machine, a freely tilttable work support, means for limiting the movement of said support in one direction, and means movable through the work support to engage the work to hold it 100 against movement during the fastening inserting operations.
16. In a fastening inserting machine, fastening inserting mechanism comprising a nozzle, a freely tilttable work support to 105 press the work against said nozzle, means for yieldingly holding the work support in work pressing position, and means movable independently of the work support to clamp the work against movement and to 110 clench the fastenings as they are driven through the work.
17. In a fastening inserting machine, means for driving fastenings into work, a freely tilttable work support for supporting 115 the work so that fastenings may be driven at various angles into the work, means for clenching the fastenings, and a spring between the work support and the clenching means whereby relative movement may take 120 place between the support and the clenching means to effect the clenching of the fastenings.
18. In a fastening inserting machine, fastening inserting mechanism comprising a stationary nozzle, a work support for pressing the work against the nozzle, clenching means for the fastenings, and means operative to 125

press the work support against the nozzle and thereafter operate the clenching means.

19. In a fastening inserting machine, fastening inserting mechanism comprising a nozzle, a work support, manually operable means for pressing the work on the support against the nozzle, means for clenching the fastenings, and means operative to press the work support against the nozzle and thereafter to operate the clenching means.

20. In a machine of the character described fastening inserting mechanism comprising a lasting tool for wiping the upper over the side of the last and into the angle between the last and the sole margin, a work support for pressing the work against the tool, clenching means for the fastenings, and means operative to press the work on the support against the lasting tool and thereafter to operate the clenching means.

21. In a machine of the character described, fastening inserting mechanism comprising a lasting tool for tensioning the upper over the side of the last and tucking it into the angle between the last and the sole margin, a work support, clenching means for the fastenings, manually operable means for lifting the work support toward the lasting tool, and power means operative to press the work on the work support against the lasting tool and for thereafter operating the clenching means.

22. In a machine of the class described, a lasting tool comprising a fastening guiding nozzle, a fastening driver co-operating with the nozzle to drive fastenings, a work support for presenting the work to the lasting tool, and means movable relatively to the support for clenching the fastenings, said work support being movable about an axis in line with the clenching means.

23. In a machine of the character described, a lasting tool comprising a fastening guiding nozzle, a work support adjustable to present the work at any desired angle with respect to the lasting tool, and means fixed in alinement with the nozzle so as to remain stationary while said work support is being adjusted and operable to clamp the fastenings.

24. In a machine of the character described, a lasting tool comprising a fastening guiding nozzle, a work support freely adjustable at any desired angle with respect to the lasting tool, and a clenching block associated with the support and capable of maintaining its clenching surface always at the same angle and in vertical alinement with respect to the fastening guiding nozzle irrespective of the adjustment of the work support.

25. In a machine of the character described, a lasting tool, comprising a fastening guiding nozzle, a work support freely

adjustable to present the work at any desired angle with respect to the lasting tool, and fastening clenching means associated with said work support for movement relatively thereto and constructed and arranged so that adjustment of the work support does not disturb the angular relation of the clenching means to the nozzle.

26. In a machine of the character described, a lasting tool comprising a fastening guiding nozzle, a support having an inclined work supporting surface arranged to be adjusted at any desired angle with respect to the lasting tool, and a clenching block located substantially at the middle of the inclined work supporting surface, the construction and arrangement being such that as a result of relative angular adjustment between the clenching block and the work support the clenching block is left in direct vertical alinement with the nozzle with its angular relationship to the nozzle undisturbed.

27. In a machine of the character described, means for operating on work, a freely tiltable work support relatively movable with respect to the work operating means to permit of the insertion and removal of work, and means movable in straight-line reciprocation through the work support to co-operate with the first mentioned means in operations on the work.

28. In a machine of the class described, a tool for operating on work, a freely tiltable work support relatively movable with respect to the tool to permit of the insertion and removal of work, and a second tool located in the same plane with the first mentioned tool and movable in said plane and relatively to the work support to operate upon the work.

29. In a machine of the character described, a member pivoted to be freely movable about an axis and provided with a work supporting surface having an opening therethrough, a tool movable through said opening for operating on work supported on said surface, and spring means for holding the work supporting surface normally above the operative end of the tool.

30. In a machine of the character described, a work support reciprocable toward and from work clamping position and movable freely about an axis so that the work supporting surface may be inclined to support the work at the inclination desired, and having an opening therethrough, and a tool movable through said opening to operate upon the work supported on said surface.

31. In a machine of the class described, a tool for operating on work, a work support controlled by the work so that the latter may be supported at various inclinations with respect to said tool, and a second tool

movable through the work support to coöperate with the first mentioned tool in operations on the work.

32. In a machine of the class described, a tool for operating on work, a second tool located in the same plane with the first-mentioned tool and movable in said plane to coöperate with said tool in operations

upon the work, and a work support located on both sides of the second tool and freely 10 movable about an axis passing through the second tool for presenting the work at various inclinations during operations thereon.

In testimony whereof I have signed my name to this specification.

FRANK W. WARD.
